DESIGN FOR A VACUUM CLEANER CASING

Frederick K. Storm, Jr., Los Angeles, Calif.

Application January 8, 1945, Serial No. 117,342

Term of patent 14 years

(Cl. D9—2)

To all whom it may concern:

Be it known that I, Frederick K. Storm, Jr., a citizen of the United States, residing at Los Angeles, in the county of Los Angeles, State of California, have invented a new, original, and ornamental Design for a Vacuum Cleaner Casing, of which the following is a specification, reference being had to the accompanying drawing, forming part thereof.

Fig. 1 is a side elevational view of the vacuum cleaner casing showing my new design.

Fig. 2 is a plan view thereof.

Fig. 3 is a front view thereof.

Fig. 4 is a rear view thereof.

I claim:

The ornamental design for a vacuum cleaner casing, substantially as shown.

FREDERICK K. STORM, JR.
